UNITED STATES PATENT OFFICE.

OSCAR W. MORTENSON, GUNNAR E. THELIN, AND KARL FRANK NORRHAGEN, OF CHICAGO, ILLINOIS.

TIE PRESS.

Application filed March 25, 1927. Serial No. 178,200.

This invention relates to improvements in tie presses, and has for one of its principal objects the provision of a device which is readily available and quickly operated, and which will enable the user thereof to satisfactorily press and keep in desirable condition ties or cravats with a minimum expenditure of time and labor.

One of the important objects of this invention is to provide, in a tie press, means for satisfactorily pressing or smoothing out a tie, while at the same time guarding against any possibility of the filler member or body of the tie showing its shape through the silken or other outer covering, which ordinarily happens in the tie presses heretofore used.

Still another and further important object of this invention is to provide, in a tie press or the like, a device composed of a minimum of parts and of a simple construction, whereby the same will be easy of manufacture and capable of being sold at a low price, enabling the user to keep and operate several, whereby the number of ties can be kept in first-class condition at all times.

Other and further important objects of the invention will be apparent from the disclosures in the accompanying drawings and following specification.

The invention, in a preferred form, is illustrated in the drawings and hereinafter more fully described.

In the drawings:

Figure 1 is a perspective view of the improved tie press of this invention, showing the same in open position.

Figure 2 is a detail view of one of the elements of the tie press.

Figure 3 is a sectional view illustrating the hinge construction of the element shown in Figure 2.

Figure 4 is a top plan view of the tie press, showing the same in closed position and with a tie therein.

Figure 5 is an end view of the tie press, illustrating its operation as applied to a tie, the tie being shown in section.

As shown in the drawings:

The reference numeral 10 indicates generally the base or bottom plate of the improved tie press of this invention, the same being preferably composed of a piece of spring steel or the like, having the edges 12 turned downwardly and rounded as best shown in

Figures 1 and 5, to provide smooth edges, and 55 also to allow for the application of hinge pins and the like.

Mounted upon the base member 10 is a strip of felt or other similar material 14, the same being either glued or otherwise attached to 60 the base, or merely laid thereon in a removable manner, if desired.

Hingedly attached to the rear edge of the base 10 by means of hinge plates 16 is a cover member 18, which is preferably composed of 65 hard rubber, bakelite, or similar material, and which also is preferably slightly resilient.

Adapted to co-operate with this cover member 18 is a thick sheet or strip of felt or similar material 20, which is preferably 70 hinged at its rear edge by means of a series of hinges 22 to the base plate 10. This member 20 is made separately movable from the cover plate 18 so as to allow of the proper positioning and smoothing of a tie in the tie press before the cover 18 is clamped down.

As best shown in Figures 1 and 4, clamping members 24 in the form of resilient metal loops or the like are hingedly mounted at the rear of the base 10 in the downwardly turned edge 12 and extend across the cover member 18, having locking members 26 in the form of similar but smaller wire loops co-operating therewith, said wire loops 26 being hingedly mounted in the forward rolled edge 85 of the plate 10. It will be noted that the members 24 are curved slightly upwardly so as to allow of the application of considerable pressure upon the cover member 18 when the device is locked in position on a 90 tie.

Adapted to co-operate with the tie press, and forming one of the essential features thereof, is a tie holding member formed of two portions 30 and 32, hinged together at or adjacent their middle by means of a hinge element 34, as best shown in Figures 2 and 3. The member 30-32 is wedge-shaped, the portion 30 being broader to accommodate the broad outer portion of an ordinary tie, and the device 30-32 is adapted to be slipped into a tie 36, as best shown in Figure 5, special reference being had to the positioning of the tie filler or body member 38 which forms an essential portion of silk ties.

When the member 30-32 is inserted into a tie, approximately one-half of the tie is brought rearwardly and under the member

30—32, and either placed into the tie press for pressing, or left outside thereof if pressing of that portion is not necessary.

The member 30—32 is then laid into the press on top of the felt 14 and all wrinkles carefully smoothed out, when the felt member 20 is placed on the top thereof. In this operation the wrinkles are smoothed out with the fingers, the flexibility of the felt member 10 20 allowing of very careful operation. If desired, the member 20 may be moistened so as to facilitate the pressing process. The member 30—32 is so adjusted with respect to the body portion 38 of the tie so as to 15 eliminate any chances of the outline of the body portion 38 showing through the silken covering 36 when the tie is removed from the press. The member 30—32 is hinged so as to allow of a ready doubling over of this 20 member and its insertion into the tie press, providing a very compact apparatus which is easily transported and requires very small space, as in a suit-case or the like.

It will be evident that herein is provided 25 a tie press which is particularly efficient, readily operated, and requires very small space, while at the same time fulfilling the

requirements of a device of this sort very satisfactorily.

We are aware that many changes may be 30 made and numerous details of construction varied throughout a wide range without departing from the principles of this invention, and we therefore do not purpose limiting the patent granted hereon otherwise than 35 as necessitated by the prior art.

We claim as our invention:

A tie press, including a base, a cover hingedly mounted on the base, and a strip of relatively soft material hingedly mounted between the base and the cover, and hinged means for locking said cover in position with respect to the base and said soft material, said means comprising U-shaped metallic bars curved upwardly from the cover to afford a 40 45 resilient pressure when in locked position, the hinge axis of said locking bars being parallel to the hinge axis of the press cover.

In testimony whereof we affix our signatures.

OSCAR W. MORTENSON.
GUNNAR E. THELIN.
KARL F. NORRHAGEN.
